UNITED STATES PATENT OFFICE

2,559,256

TIE BAR FOR HEAT EXCHANGE HEADERS

William F. Matheny, Tulsa, Okla., assignor to
Arrow Industrial Manufacturing Company,
Tulsa, Okla., a corporation of Oklahoma

Application May 17, 1948, Serial No. 27,525

1 Claim. (Cl. 285—5)

1

This invention relates to tie bars for heat exchanger headers.

One important object of the invention is to improve on the usual cast iron tie bar of flat plate type wherein such tie bar is cast integrally with the header walls.

Another important object of the invention is to provide a novel form of tie bar employing a steel bolt to handle the stresses developed in high pressure headers.

A further important object of this invention is to provide a novel high pressure tie bar including a hollow circular tie bar cast integrally with the header body and employing a nickel steel bolt and brass sleeve.

A still further object of the invention is to form the tie bars of circular cross-section thereby effecting an increase in strength of such tie bars without materially increasing the weight or decreasing the number of tubes in the header.

Again, an object of the invention is to provide a circular form of tie bar which will eliminate the common flat tie bar, the effect being to decrease turbulence and loss of pressure.

Still another object of the invention is to provide a circular tie bar so as to allow greater area of metal to tie to the faces of the header, thereby decreasing the amount of shrinkage cracks and consequent loss of castings.

Yet another object of the invention is to provide a brass sleeve or gasket between the circular tie bar and the steel bolt used herein.

Still further, an object of the invention is to provide a tubular tie bar for low pressure work wherein the tie bar is provided with a diametric slot and an open end for connection of a tube leading to another header.

With the above and other objects in view, the invention consists in general of certain novel details of construction and combinations of parts hereinafter fully described, illustrated in the accompanying drawings, and particularly claimed.

In the accompanying drawings, like characters of reference indicate like parts in the several views, and

Figure 1 is a fragmentary face view of a portion of a high pressure header constructed in accordance with this invention;

Figure 2 is a section on the line 2—2 of Figure 1;

Figure 3 is a section on the line 3—3 of Figure 2;

Figure 4 is a section similar to Figure 2 but showing a modified form of the invention;

Figure 5 is a section on the line 5—5 of Figure 4;

Figure 6 is a view similar to Figure 2 but showing a second modification of the invention; and

2

Figure 7 is a section on the line 7—7 of Figure 6.

In each form of the invention here shown, the back wall of the header is indicated at 10 and the front wall at 11. In devices of this character, the front and back walls generally consist of large, flat plates of cast iron formed integrally with edge walls 12.

The front wall is provided with a multiplicity of tube openings 13 and the front and back walls are tied together by tie bars. In the form shown in Figures 1, 2 and 3, the tie bars include tubular members 14 cast integrally with the remainder of the header. Fitted in the members 14 are brass sleeves 15. Within the sleeves 15 are bolts 16 preferably of nickel steel. These bolts are heated and inserted in the brass tubes. The nuts 17 on these bolts are then screwed up and the bolts allowed to cool. This puts considerable initial tensile stress on the bolts, thus holding the front and back walls from springing apart.

In the form shown in Figures 4 and 5, the front and back walls are connected by integral tubular tie bars 18 on which are fitted, without the use of brass tubing, tie bolts 19 provided with nuts 20, and these bolts are applied like the bolts 16 by heating for longitudinal expansion, inserting in the cast tie bars, tightening the nuts 20 and cooling.

For low pressure work, the form shown in Figures 6 and 7 may be used. Here the integrally cast tie bar 21 has a diametrically disposed slot 22 and opens through the walls 10 and 11. The opening through the wall 10 is plugged as at 23, while the opening through the wall 11 may have a pipe 24 fitted therein for communication with the opposite header or the like.

What is claimed is:

In a header for the purpose set forth, front and rear walls of cast iron, tubular tie bars connecting said walls, said tie bar opening through said walls and having a diametrically disposed slot therethrough, a plug closing the tie bar at one wall and a pipe leading from the tie bar at the other wall.

WILLIAM F. MATHENY.
